(57) **ABSTRACT**

A modular and configurable muscular physical rehabilitation and training system that is a total body fitness system designed to promote strengthening and creation of muscle mass using free weights. Free weights simulate real-life situations and promote whole body stabilization. Free weights allow more variations in the range of motion than using modern machines. The system allows the flexible and configurable use of muscle contractile activities utilizing free weights and proper techniques. This is done in a space-saving, compact, safe, configurable, and practical configuration that can be used with a plurality of participants supported by a single trainer/therapist.

**PHYSICAL WORKOUT SYSTEM AND
METHOD**

**CROSS-REFERENCES TO RELATED
APPLICATIONS**

This application is a continuation-in-part of U.S. patent application Ser. No. 17/974,144 filed on Oct. 26, 2022, which is a continuation-in-part of U.S. patent application Ser. No. 17/726,137 filed on Apr. 21, 2022, which claims the benefit of U.S. Provisional application Ser. No. 63/177,499 filed on Apr. 21, 2021. Application Ser. No. 17/974,144 also claims the benefit of U.S. provisional application Ser. No. 63/418,794, filed on Oct. 24, 2022. All of which are incorporated herein by reference.

BACKGROUND

This application relates generally to an exercise apparatus and method of use.

Conventional approaches for exercise equipment, in particular weightlifting equipment, fail to provide an integrated approach that is conducive to effective use while efficiently utilizing space. Current systems also do not utilize therapists/trainers in an efficient manner, and are inflexible and not adaptable to easy reconfiguration. A solution to these problems is desired.

SUMMARY

Provided are a plurality of example embodiments, including, but not limited to, the configurable embodiments shown in the attached figures. Due to the reconfigurable nature of the system, an almost limitless range of embodiments can be supported.

Also provided is a method of providing training or a therapy to a plurality of participants, said method comprising the steps of: providing a modular physical rehabilitation system comprising a plurality of configurable units, each one of said configurable units being configured to be placed adjacent to another one of said configurable units, wherein each one of said configurable units can be configured to support one or more of said participants with exercise equipment including free weight support, and provide therapy and/or training to each one of said participants in a concurrent manner using one or more therapists/trainers.

Further provided is the above method wherein each one of said configurable units includes at least 2 (front) exercise stations on a longitudinal side and at least one (side) exercise station on a transverse side, using a single unit. Adding an additional unit can double the number of stations.

Still further provided are any of the above methods wherein at least one of said exercise stalls is configurable with equipment including free weights for performing any of bench presses, squats, shoulder presses, curls, stationary biking, bent rows, and shoulder shrugs.

Even further provided are any of the above methods wherein a side exercise station is configurable with equipment for performing dip station/chin ups.

Further provided is a system to provide training and/or a therapy to a plurality of participants, comprising: a cage having a frame including: a front beam, a back beam, a first side beam connected to said front beam and said back beam on one side of the cage, and a second side beam connected to said front beam and said back beam on another one side of the cage, a first front leg attached at or near a junction of said front beam and said first side beam, a second front leg

attached at or near a junction of said front beam and said second side beam, at least one sliding leg configured to slide along the front beam and be temporarily secured at one of a plurality of potential locations along that front beam; and at least one adjustable and movable exercise stations configured to mount on one or more of said legs.

Still further provided is a system to provide training and/or a therapy to a plurality of participants, comprising: a cage having a frame including: a front beam, a back beam, at least one wall beam connected to said back beam, said at least one wall beam being configured for attaching to a wall, a first side beam connected to said front beam and said back beam on one side of the cage, and a second side beam connected to said front beam and said back beam on another one side of the cage, a first back leg connected at or near a junction of said first side beam with said back beam, said first back leg being configured for fixedly connecting to a floor; and a second back leg connected at or near a junction of said second side beam with said back beam, said second back leg being configured for fixedly connecting to the floor; a first front leg attached at or near a junction of said front beam and said first side beam, said first front leg being configured for fixedly connecting to the floor, a second front leg attached at or near a junction of said front beam and said second side beam said second front leg being configured for fixedly connecting to the floor, at least one pair of sliding legs, each sliding leg being configured to slide along the front beam and be temporarily secured at one of a plurality of potential locations along that front beam; a plurality of adjustable and movable exercise stations each configured to mount on one or more of said legs, wherein at least one of said adjustable and movable exercise stations is configured for a different exercise than another one of said adjustable and movable exercise stations.

Also provided is a method using any of the above systems for providing training and/or a therapy to a plurality of participants, said method comprising the step of providing therapy or training to each one of said participants in a concurrent manner using the system with one or more therapists/trainers supporting said training/therapy.

Also provided is system configured to provide training and/or a therapy to a plurality of participants, comprising: a plurality of workstations, wherein at least one of said workstations is configured to support a different exercise activity than another of said workstations; and a structural cage including a mounting structure configured to attach to a wall and also including a first working side structured to engage one or more of said plurality of workstations, said structural cage also including a second working side that is structured to engage one or more other ones of said plurality of workstations.

Still further provided is a system configured to provide training and/or a therapy to a plurality of participants, comprising: a plurality of workstations including at least one free weight spotter bench, at least one dip station, and at least one squat station; at least one weight hanger configured to store free weights; a structural cage including a mounting structure configured to attach to a wall and also including a first working side structured to engage one or more of said plurality of workstations, said structural cage also including a second working side that is structured to engage one or more other ones of said plurality of workstations, said structural cage also including a third working side that is structured to engage one or more still other ones of said plurality of workstations, said structural cage comprising

one or more adjustable legs configured to slide horizontally along one of said working sides, said adjustable legs being length adjustable.

The first working side of the system can be configured with at least a first one of the plurality of different workstations, and the said second working side can be configured to be at a right angle with said first working side, said second working side being configured with at least a second one of the plurality of workstations, and the third working side can be configured to be at a right angle with said first working side, said third working side being configured with at least a third one of the plurality of workstations.

Also provided are any of the above systems being used in a method for providing training and/or therapy to a plurality of participants, said method comprising the step of providing therapy or training to each one of said participants in a concurrent manner using said system with one or more therapists/trainers supporting said training/therapy.

Still further provided are additional example embodiments, some, but not all of which, are described hereinbelow in more detail and/or in the claims.

BRIEF DESCRIPTION OF THE DRAWINGS

The features and advantages of the example embodiments described herein will become apparent to those skilled in the art to which this disclosure relates upon reading the following description, with reference to the accompanying drawings, which show the various components of the system in substantial detail, including:

FIG. 1 shows a perspective view of an example single unit being used by a user;

FIG. 2 shows a perspective view of an example single unit with a different configuration;

FIG. 3 shows a front view of the example single unit of FIG. 1;

FIG. 4 shows a side view of the example unit of FIG. 1;

FIG. 5 shows a corner of the units of FIGS. 1 and 2 with hardware for fixedly connecting the units to a wall;

FIG. 6 shows another view of a corner of the units of FIGS. 1 and 2 with hardware for fixedly connecting the units to a wall;

FIG. 7 shows a side view of an example bottom post stand;

FIG. 8 shows a perspective view of an example system comprising a pair of the units of FIG. 2 configured together to form a larger system having a different exercise station configurations;

FIG. 9 is a front view of an example system comprising a pair of the units of FIG. 2 configured together to form a larger system having a pair of exercise stations using free weights;

FIG. 10 is a back view of an example system comprising a pair of the units of FIG. 2 configured together to form a larger system;

FIG. 11 is a side view of the example system of FIG. 8;

FIG. 12 is a view of an example configuration of a slidable mounting bracket for use by movable legs of any of the example systems;

FIGS. 13A and 13B show different perspectives of an example bracket with wheels for use in the mounting bracket of FIG. 12; and

FIG. 14 shows an example system being utilized by multiple patients.

DETAILED DESCRIPTION OF THE EXAMPLE EMBODIMENTS

This system includes various improvements to the Squat Rack disclosed in U.S. Pat. No. 7,635,322, issued on Dec.

22, 2009, and incorporated herein by reference in its entirety. Also incorporated herein is an application to a Suspended Squat Rack as disclosed in U.S. Pat. No. 7,025,712 filed on Sep. 5, 2002. This application also incorporates the entire disclosure, drawings, and appendices of U.S. provisional patent application Ser. No. 63/177,499 filed on Apr. 21, 2021 and U.S. provisional patent application Ser. No. 63/418,794, filed on Oct. 24, 2022.

Provided is a muscular physical rehabilitation system that 10 is a total body fitness system designed to promote strengthening and creation of muscle mass using free weights. Free weights simulate real-life situations and promote whole body stabilization. Free weights allow more variations in the range of motion than using modern weight lifting machines. 15 The system allows the use of muscle contractile activity utilizing free weights and proper techniques. This is done in a space-saving, compact, safe, stable, and practical configuration as disclosed herein. The system offers a full body rehabilitative workout with a much smaller footprint than 20 typical units on the market and provides the ability to rehabilitate more patients and offer less wait time. The system can be provided as a multi-free weight device with plural uses. The apparatus can be used as a physical therapy device that targets all muscles of the body. Larger dimensions of the material changes allow the device to handle heavier weights and changes the device to become a strength training device. A potential ratio of exercises with one unit is 16 to 1. A second back-to-back unit increases the number of exercises to 32 to 1. An addition of rack of dumbbells only 25 increases the exercise ratio, because all exercises can become isolated.

One modification to the '322 disclosure is the addition of a configurable cage. The addition of the new leg rolling system and locking devices (pins) in conjunction with the 30 locator holes in the I beam(s) the frame to match up with the locking pins on roller assemblies attached to a top portion of the linearly movable legs will reduce the risk and guess work in finding the right locations between shoulder width and Olympic size exercises. This variation of rollers on both 35 sides of the bottom lip of the I-Beam adds to the smoothness of reconfiguration of exercises.

Improved additions are the wall supports, and supports that attach system to system, back to back for integrating two cages (units) into a larger workout system capable of 40 supporting multiple patients. Attaching the cage system to the floor was another addition to add to the stability and sturdiness of the system.

A single unit (cage), such as shown in FIGS. 1 and 2, provides several variations of rehabilitation exercises. For 45 example, three or more exercise stations can be set up configured for the individuals unique size, such as to accommodate whole-body workouts. A single system can be configured for use by three different users, or for circuit training a single user. Also provided is a one-dip and a chin-up station.

By adding a second unit with the first unit, back to back, as shown in FIG. 8, the system can be configured to accommodate an additional three or more stations with six total exercise stations. FIG. 1 shows a single participant 50 using the system, but up to six or more could be accommodated with the dual unit configuration. Each unit can be provided of example dimension 5 ft. deep, 12 ft. wide, and 100 inches tall. The dual unit could then be approximately 55 10 feet deep.

The system is comprised of hangers with safety hooks that 60 allow the user to roll and create individual workstations for shoulder-width exercises, up to Olympic size exercises. The

design allows for ease of re-configuration, and substantial flexibility in station design. The exercise stations can be mixed and matched as desired, using unique or duplicate stations in various adjustable configurations. This allows for generous flexibility and variability in the exercises to be supported.

For example, there can be provided 2 exercise stalls on the longer (longitudinal) front or back side of the cage which permit two areas to do bench presses (all variations), squats, shoulder press, curls (shoulder width), stationary bike, bent rows, shoulder shrugs, all with free weights. Two or more side stations (transverse side) can be provided that can have 2 bench press stations or other exercise stations at the same time. The side stations offer, for example, two exercises, dip station/chin ups section. Or side stations can be moved to the front/back stations, and vice versa.

By the addition of a second caged unit, the number of stations can be doubled, and one can have up to 6 or more physical therapy patients being rehabilitated at the same time with the assistance of an on site physical therapist. One target market is the physical therapy market, and eventually into physical fitness. This system provides the physical therapy market with a practical, flexible, and customizable free weight system for performing physical therapy and fitness.

From the exercise stand-point, one can set up one single unit with 3 or 4 different exercises (with each supporting a separate participant) and be utilized as a circuit training device. A spotter can change exercises and keep the lifter in constant mode to reach total muscle failure. Adding a second unit will expand the system to support additional stations, as would adding a third unit, or more.

This system could be utilized as a Freeweight P.T. device that would be considered a physical therapy device, that will utilize one or more licensed physical therapists to assist in process of free weight physical rehabilitation. One Free Weight P.T. (one unit) can rehabilitate up to 3 patients at the same time. If a second device (unit) is installed back to back to another Freeweight P.T. device, one could rehabilitate up to 6 patients, with a constant changing of exercises by the physical therapist.

Freeweights are very beneficial for rehabilitation for simple reason that it makes the patient lift, control, and balance the weight, improving on all of those capabilities through practice and training.

The Freeweight P.T. device need not be a heavy load bearing device, but rather a device that can be utilized for teaching the patient the full range of motion, and science behind lifting weights for rehabilitation that will stay with the patient for a full recovery or perhaps stronger than before for the rest of the patient's life.

FIGS. 1 and 2 show a first perspective view of a single unit system 100, 100A to be used by a patient 10. This system is comprised of a cage frame having front beam 105, back beam 106, and side beams 104 connecting the front beam 105 to the back beam 106 on alternate sides. The cage includes front legs 101, 102, 110, and center front leg 141, and two back legs 103 for supporting the beams 104, 105, and 106 along with the equipment used at the exercise stations. As shown, the legs 103 have a fixed foot bracket 120, whereas legs 101, 102, and 110 have a bottom post stand 142 provided for additional stability. Some of the bottom post stands 142 utilize fixed foot brackets 120, whereas center front leg 141 and other bottom post stands 142 utilize adjustable foot brackets 150 to adjust the unit for uneven surfaces and/or warping and bowing.

Note that the fixed brackets 120 are on the legs and posts found at sides (and back) of the unit, and can be provided with a pair of holes in their base to secure them to the floor using securing hardware (e.g., slag bolts or screws). These legs 101, 110, 103 are permanently connected to the respective beams 104, 105, 106 using brackets and bolts. The adjustable brackets 150 are typically put on the inner legs and posts, with the inner legs 102, 141 being sliding legs that are slideable in the horizontal direction along front beam 105 until being secured to the front beam 105 using a locking pin on bracket 161 to engage a hole in the front beam 105, discussed in more detail hereinbelow. The top frame includes the front beam 105, a back beam 106, side beams 104, and mounting beams 119 each connected to a wall mounting bracket 119a.

All of the legs and beams could be provided at any desired lengths for various implementations. Generally, the height of the example assembled and installed single unit is about 5 ft. deep, 12 ft. wide, and 100 inches tall. Alternative dimensions are easily accommodated by changing the lengths of the various beams and legs, and/or by using extension brackets and braces.

The legs are outfitted with various holes that can be utilized with the optional, movable components described herein. This allows multiple devices to be installed on the legs, and it allows the devices to be moved vertically up-and-down to change their effective height, such as to customize device placement to the needs of individual users, such as taller versus shorter users. These components can be mounted using pins, screws, or other fasteners to hold them in place in a removable manner. The figures show these holes in various configurations that could be modified as desired for alternative embodiments.

Note that the various legs and beams are connected together using braces and connecting hardware. The particular types of such hardware could be any effective components known in the art or developed in the future. The various components can be constructed of a strong material, such as steel, steel alloys, composite materials, or other materials that can sustain the types and quantities of weight that are used in the training operations to be supported. For example, the legs at the left and right ends of the device (front and back) can be fixedly connected to the beams, such as at, or near, junctions in the beams themselves. The figures show the connections at the junctions of the front beam 105 and the side beams 104 (left and right front legs 110, 101), and at the junctions of the back beam 106 and the side beams 104 (left and right back legs 103). However, the legs could be mounted on only the side beams, or the front/back beams, as desired, although for structural purposes it is suggested that they be mounted near the cross beams. Examples of such hardware and additional components for use with the system are provided in the disclosure, drawings, and/or appendices of U.S. provisional patent application Ser. No. 63/177,499; and U.S. provisional patent application Ser. No. 63/418,794; both incorporated herein by reference.

Of particular note in an example embodiment, the front beam 105 is comprised of an "I" beam having holes 163, a top lip, and a bottom lip 105a as shown in FIG. 12. Although the example front beam is shown with 5 holes, more holes can be added (e.g., 6, 7, 8, 9, 10 or more) to refine the ability to adjust the space between the adjustable legs 102, 141. The adjustable (moveable) legs 102, 141 have a bracket 162 that is connected via connector hardware (e.g., a bolt) to a bracket 161 that is configured to slide along the lip 105a and that is secured by using a locking pin 164 that engages one of the holes 163 to hold the bracket 161, and thereby the legs

102, 141 in place. Removing the pin allows the leg to be “rolled” along the beam 105 to move the leg’s horizontal position. As suggested above, the number of holes 163 can be increased, as desired, to support more finely adjustable legs in the horizontal position, as desired. The number of adjustable legs could also be increased, if desired, to greater than 3 (or reduced to 1 or 2). This allows accommodation of differently spaced equipment, such as longer weight barbells to support users with wider shoulders, for example.

The example bracket 161 is shown in FIGS. 13A and 13B with one of pair of wheels 165 and a corner bracket 166 along with connecting hardware (bolts and nuts). The wheels 165 allow the legs connected to the respective brackets 161 to slide along the beam 105 for adjusting. By adding additional holes 163, the placement of the legs 102, 141 are adjustable along the length of the beam 105. The wheels 165 can utilize any rubber, plastic, or metal wheel that may utilize bearings to facilitate movement. In some cases, a single wheel may be used instead of a pair, or rollers could be used instead of wheels, for example.

The example systems provide a plurality of exercise workstations and components for training and rehabilitation purposes, including a dip station assembly 117 installed on one of the legs 103. Note that any station could be installed on other legs, as desired.

An optional pulley weight system is shown installed in unit 100 of FIG. 1 having upper pulleys 133 installed on the right side of the unit on legs 103, 101 respectively, with lower pulley 134 installed on leg 101. The pulley system has a handle 132 at one end and a weight rack 131 at the other end for weight training. Alternatively, unit 100A of FIG. 2 shows a unit having a pair of large weight/squat catches 124 installed on legs 101 and 102, respectively, rather than the pulley weight system.

A pair of weight catchers 125 are installed on legs 110, 102 at the front of unit 100, and are associated with a free weight barbell 108 held by a pair of barbell hangers 123 with a spotter bench 127 installed therewith to form an adjustable squat rack subsystem. Weight hanger 111 is provided to hold weights for the barbell 108. A weight post storage assembly 109 is provided installed on leg 141 to store additional weights for use by the free weight components of the system.

FIG. 3 shows a front view of the unit 100 of FIG. 1. Note the wrench 143 for adjusting various fasteners can be hung from a hole in the leg 110, or other legs, and a different wrench 128 is shown on leg 141.

FIG. 4 shows a side view of the embodiment 100 of FIG. 1, whereas FIGS. 5 and 6 show a corner view of that embodiment with detail for the wall bracket 119a that can be installed on a wall to stabilize the system. FIG. 7 shows a more detailed view of the side of the bench 127 with bottom post stand 142 and brackets 120.

FIG. 8 shows perspective view of an example embodiment of an extended system 200 using two separate units 100b, 100c configured together one in front of the other. The front unit 100b is basically the unit 100A shown in FIG. 2, but without wall mounting brackets 119a and with extension beams 119c replacing the mounting beams 119. The beams 119c then attach to front beams 105 of back unit 100c, which is similar to unit 100A of FIG. 1 but with the arrangement of components reversed right to left.

Note that alternative station assembly 117a is utilized on the left side of the extended system 200. Note also that when two units 100b, 100c are used, the front beam 105 of unit 100c is actually in the back of the assembled unit, and back beam 106 is in front of the front beam 105, as the two units

are reversed in direction with respect to each other (i.e., rotated 108°), in the shown example. This allows exercise stations to be put on the outer circumference of the frame, rather than on an interior part, making access by users easier, and avoiding the need for users to be in an interior of the system cage.

Hence, extended system 200 shows that a modular system can be provided that enables at least a doubling of the number of potential stations for larger setups and for serving 10 larger numbers of patients/trainees.

FIG. 9 shows a front view of an example extended system 200a that is modified from system 200 by adding a second free weight barbell system on the front with barbells 108a. FIG. 10 shows a back view of the system 200, whereas FIG. 15 11 shows a left side view of the system 200.

The system can be used to train or rehabilitate between 3 to 6 patients at the same time and create an efficient physical therapist job. The apparatus has dual use and can be used as a strength and conditioning device with an upgrade in 20 material. The concept and design remain the same. The rehab model consists of 2"×2" tubing. Strength training models would consist of 2"×3" tubing. FIG. 14 shows an example system of two modular units configured together for being utilized by multiple patients.

25 The average current wage of a physical therapist is between \$47.00 and \$51.00 per hr. This system permits up to 3 to 6 patients per hour based on the purchase of one unit (e.g., 3 patients) or two units back-to-back (e.g., 6 patients). Hence, the system can provide 3- and 6-fold profit per unit sold. This system will create a greater need for both a physical therapist and a sports medicine representative.

30 Note that the average current wage of a Sports Medicine Technician is \$19.99 per hr. By using the system, such a technician can obtain between 3- and 6-fold profit improvements.

35 Many other example embodiments can be provided through various combinations of the above described features. Although the embodiments described hereinabove use 40 specific examples and alternatives, it will be understood by those skilled in the art that various additional alternatives may be used and equivalents may be substituted for elements and/or steps described herein, without necessarily deviating from the intended scope of the application. Modifications may be necessary to adapt the embodiments to a particular situation or to particular needs without departing from the intended scope of the application. It is intended that the application not be limited to the particular example implementations and example embodiments described herein, but that the claims be given their broadest reasonable interpretation to cover all novel and non-obvious embodiments, literal or equivalent, disclosed or not, covered thereby.

45 What is claimed is:

1. A system configured to provide training and/or a therapy to a plurality of participants, comprising:
50 a plurality of workstations, wherein at least one of said workstations is configured to support a different exercise activity than another of said workstations; and a structural cage including a mounting structure configured to attach to a wall and also including a first working side structured to engage one or more of said plurality of workstations, said structural cage also including a second working side that is structured to engage one or more other ones of said plurality of workstations;
55 said structural cage also including a vertical first front leg and a vertical second front leg; and

said structural cage also including a horizontal front beam connecting said first front leg with said second front leg, said front beam being configured to connect to at least one additional leg between said first front leg and said second front leg.

2. The system of claim 1, wherein said mounting structure includes hardware configured for securing said cage to the wall.

3. The system of claim 1, wherein said additional leg is configured to slide horizontally along one of said working sides, said adjustable leg also being configured to interact with a respective one of said workstations.

4. The system of claim 3, said additional leg being length adjustable.

5. The system of claim 3, wherein said first front leg and said second front leg are configured to fixedly attached to said front beam, said first leg and said second leg also being configured to connect to different ones of said plurality of workstations.

6. The system of claim 5, said first and second legs being configured to attach securely to a floor.

7. The system of claim 1, wherein said plurality of workstations include at least one free spotter weight bench, at least one dip station, and at least one squat station.

8. The system of claim 7, wherein said plurality of workstations include at least one additional free weight spotter bench, and at least one additional dip station.

9. The system of claim 7, wherein said plurality of workstations also includes at least one pulley weight system.

10. The system of claim 1, wherein said plurality of workstations includes at least one pulley weight system.

11. The system of claim 1, further comprising a third working side that is structured to engage one or more of said plurality of workstations.

12. The system of claim 1, further comprising a fourth working side that is structured to engage one or more of said plurality of workstations.

13. The system of claim 1, wherein said cage is structured in a modular manner to add one or more additional working sides.

14. The system of claim 1, further comprising one or more weight hangers configured to store free weights.

15. The system of claim 1, wherein said cage comprises: said front beam being configured as part of one of said working sides,

a back beam configured to be parallel to the wall, a first side beam connected to said front beam and said back beam on one side of the cage, and

a second side beam connected to said front beam and said back beam on another one side of the cage, wherein at least one of said first side beam and/or said second side beam is configured as part of another one of said working sides;

said first front leg being attached at or near a junction of said front beam and said first side beam,

said second front leg being attached at or near a junction of said front beam and said second side beam; and

said additional leg configured to support the cage on surface and to slide horizontally along the front beam and be temporarily secured at one of a plurality of potential locations along that front beam.

16. The system of claim 1, wherein

said first working side is configured with at least a first one of the plurality of different workstations in an adjustable manner; and wherein

said second working side is configured to be at a right angle with said first working side, said second working

side being configured with at least a second one of the plurality of workstations in an adjustable manner, said second one of said workstations being configured to support a different exercise activity than said first one of said workstations.

17. A method using the system of claim 1 for providing training and/or therapy to a plurality of participants, said method comprising the step of providing therapy or training to each one of said participants in a concurrent manner using said system with one or more therapists/trainers supporting said training/therapy.

18. A system configured to provide training and/or a therapy to a plurality of participants, comprising:

a plurality of workstations including at least one free weight spotter bench, and one or both of a dip station and/or a squat station;

a structural cage including a mounting structure configured to attach to a wall and also including a first working side structured to engage one or more of said plurality of workstations, said structural cage also including a second working side that is structured to engage one or more other ones of said plurality of workstations, wherein

said structural cage includes a vertical first front leg attached to a vertical second front leg via a horizontal front beam, said front beam being configured to receive an additional leg, and wherein

said first working side is configured with at least a first one of the plurality of different workstations; and wherein

said second working side is configured to be at a right angle with said first working side, said second working side being configured with at least a second one of the plurality of workstations.

19. The system of claim 18, further comprising a third working side that is structured to engage one or more of said plurality of workstations.

20. The system of claim 19, further comprising a fourth working side that is structured to engage one or more of said plurality of workstations.

21. The system of claim 18, wherein said cage is structured in a modular manner to add one or more additional working sides.

22. The system of claim 18, wherein said additional leg is configured to comprising one or more adjustable legs configured to slide horizontally along said front beam to form one of said working sides to interact with a respective one of said workstations.

23. A system configured to provide training and/or a therapy to a plurality of participants, comprising:

a plurality of workstations including at least one free weight spotter bench, at least one dip station, and at least one squat station;

at least one weight hanger configured to store free weights;

a structural cage including a mounting structure configured to attach to a wall and also including a first working side structured to engage one or more of said plurality of workstations, said structural cage also including a second working side that is structured to engage one or more other ones of said plurality of workstations, said structural cage also including a third working side that is structured to engage one or more still other ones of said plurality of workstations, said structural cage comprising one or more adjustable legs

configured to slide horizontally along one of said working sides, said adjustable legs being length adjustable, wherein

said first working side is configured with at least a first one of the plurality of different workstations, and 5 wherein

said second working side is configured to be at a right angle with said first working side, said second working side being configured with at least a second one of the plurality of workstations, and further wherein 10

said third working side is configured to be at a right angle with said first working side, said third working side being configured with at least a third one of the plurality of workstations.

24. The system of claim **23**, wherein said cage is structured in a modular manner to add one or more additional working sides. 15
